The ornamental design for a jelly bean pillow, as shown and described.

DESCRIPTION

FIG. 1 is a left side elevational view of the jelly bean pillow shown in FIG. 7.

FIG. 2 is a right side elevational view of the jelly bean pillow shown in FIG. 7.

FIG. 3 is a front elevational view of the jelly bean pillow shown in FIG. 7;

FIG. 4 is a rear elevational view of the jelly bean pillow shown in FIG. 7;

FIG. 5 is a top plan view of the jelly bean pillow shown in FIG. 7;

FIG. 6 is a bottom plan view of the jelly bean pillow shown in FIG. 7; and,

FIG. 7 is a quartering perspective view of the jelly bean pillow of the present invention and showing the new design.
